KUZO YOSHINAGA, OF SAN FRANCISCO, CALIFORNIA.

HAT-PIN PROTECTOR.

1,118,997.

Specification of Letters Patent.

Patented Dec. 1, 1914.

Application filed February 3, 1913. Serial No. 745,876.

To all whom it may concern:

Be it known that I, Kuzo YOSHINAGA, a subject of the Emperor of Japan, residing at San Francisco, in the county of San Francisco and State of California, have invented new and useful Improvements in Hat-Pin Protectors, of which the following is a specification.

The present invention relates to improvements in hat pin protectors, the object of the invention being to provide a device of this character which will be simple in construction, effective and convenient in operation, and ornamental in appearance.

In the accompanying drawing, Figure 1 is a side view of the protector applied to a hat pin; Fig. 2 is a longitudinal sectional view thereof; Fig. 3 is a cross-sectional view on the line 3—3 of Fig. 2.

Referring to the drawing, 1 indicates a hat pin of ordinary construction.

My improved protector comprises a tubular body 2, the bore 3 of which receives the pointed end of the pin, and which is contracted at the outer end, as shown at 4, to engage the extreme end of said pin and arrest the movement of the protector upon the pin. To facilitate the passing of the protector upon the pin, its outer end is threaded 30 and screwed into a threaded central boss 6 of a concavo-convex head.

The inner end of the body of the protector is enlarged transversely as shown at 8, and formed with three radially extending guideways 9, in which are received balls 11. The outer side of said enlarged portion is conical and tapers toward the head of the pin, said guideways opening into said outer tapering surface of said enlarged portion. Surround-

ing said conical enlarged portion is a conical closure 12 having a neck 13. 14 indicates a spring formed at the center with a hole 15 surrounding said neck 13, and at the ends with holes 17 surrounding the reduced portion 4 of the end of the body of the protector, and pressed between the boss 6 and the shoulder 18 formed by said reduced portion 4, the tension of this spring acting to draw the closure toward the head of the protector.

The mode of use of the protector can be readily understood from the foregoing description. When the pointed end of the pin is inserted in the bore of the protector, the balls engage the surface of the pin, and are, by frictional contact therewith pressed in the direction of the protector head, being retained in that said position by the conical wall of the closure, which in turn is pressed toward said head by said spring. The tension of said spring, through the medium of the closure, causes said balls to press against the pin with sufficient force to prevent accidental removal. The pin can be removed, however, when desired, by pressing the sides of the spring toward one another, thereby causing the closure to move longitudinally away from the head and remove the pressure from the balls and release the pin.

I claim:

A hat pin protector comprising a tube the bore of which is contracted at one end to form a stop for the pointed end of the pin, a cap screwed to said end of the tube, the other end of the tube being enlarged and formed entirely therethrough with radially extending open-ended guideways, balls in said guideways, a longitudinally movable member surrounding said tube and formed with a neck, the inner surface of said member being conical, a curved spring one end of which engages said neck and the other is fixed, and said spring extending convexly outward between its ends in a position to be manually flattened to move said member longitudinally, said member being so arranged that by said longitudinal movement its inner surface is withdrawn from said balls.

In testimony whereof I have hereunto set my hand in the presence of two subscribing witnesses.

KUZO YOSHINAGA.
